US00D847920S

(12) **United States Design Patent** (10) **Patent No.:** **US D847,920 S**
Lien (45) **Date of Patent:** ** *May 7, 2019

(54) **EXERCISE SLED**

(71) Applicant: **USA Sports, Inc.**, Houston, TX (US)

(72) Inventor: **Louis Lien**, Bellaire, TX (US)

(73) Assignee: **USA Sports, Inc.**, Houston, TX (US)

(*) Notice: This patent is subject to a terminal disclaimer.

(**) Term: **15 Years**

(21) Appl. No.: **29/552,984**

(22) Filed: **Jan. 27, 2016**

(51) LOC (11) Cl. **21-02**

(52) U.S. Cl.

USPC **D21/691**

Primary Examiner — Robert M. Spear

Assistant Examiner — Ryan Harvey

(57) **CLAIM**

The ornamental design for an exercise sled, as shown and described.

DESCRIPTION

FIG. 1 is a top view of the design according to the invention. FIG. 2 is a bottom view of the design according to the invention.

FIG. 3 is a right side view of the design according to the invention.

FIG. 4 is a left side view of the design according to the invention.

FIG. 5 is a front side view of the design according to the invention.

FIG. 6 is a back side view of the design according to the invention.

FIG. 7 is a perspective view of the design according to the invention; and,

FIG. 8 is another perspective view of the design according to the invention.

1 Claim, 7 Drawing Sheets
